CONSERVATION OF HEAT ENERGY IN HEATING,
DRYING, AND OTHER INDUSTRIAL PROCESSES

William Wycliffe Spooner, Ilkley, England

Application August 21, 1950, Serial No. 180,678

Claims priority, application Great Britain August 25, 1949 10

4 Claims. (Cl. 34—35)

The present invention relates to the conservation of heat energy in heating, drying and other industrial processes. 15

The present invention consists in pumping a vapour, such as steam, mechanically by means, for example, of a pump or ejector to raise its pressure and thus enhance its availability. 20

The invention is especially applicable to low pressure steam which might not otherwise be usable to any material extent for industrial processes, and in many applications of the invention it will be possible to avoid loss 25 of latent heat of steam or other vapour by mechanically increasing its pressure.

In many cases low pressure steam might be available but might not be readily re-usable in accordance with the present invention because it may, for example, be mixed with air. In such cases, according to the present invention, the steam or the mixture of steam and air, which may be at low temperature and pressure, may be used for raising low pressure steam whose pressure may then be increased mechanically, as by a pump or ejector. Thus, a further feature of the present invention consists in raising steam at low pressure by heat interchange with a source of low temperature heat such as waste heat, and then mechanically increasing the pressure of the steam so raised. 30

A still further feature of the invention consists in raising steam at a pressure less than atmospheric by heat interchange with a source of low temperature heat such as waste heat, and using a pump or ejector or other mechanical means to maintain the low pressure of the steam being generated and to increase its pressure after it has been generated. 40

When steam or other vapour is raised at low pressure by low temperature waste heat, the heating medium is preferably passed round a closed circuit and repeatedly caused to flow at relatively high speed over the surfaces containing the material to be heated, so that interchange of heat can be achieved with relatively small temperature differences between the heating and heated media. 50

Thus, for example, a suitable form of heat interchanger may consist of a set of gilled heating coils or tubes in which the steam is raised, the said heating coils or tubes being arranged in a closed circuit with a fan, and the heating medium passed in closed circuit from the fan to the heating coils and from the heating coils back to the fan. Whereas in conventional heat interchangers the rate of flow of the heating medium through the system is usually about equal to the rate of inflow of the heating medium into the system, the rate of flow of the heating medium through the system in the case of my heat interchanger is much greater than and preferably a multiple of the rate of inflow of the heating medium. For example, the rate of flow of the heating medium through the fan and thus past the heating coils may be between ten and twenty times the rate of inflow of the heating medium. 55

The invention is very applicable, for example, to the conservation of heat energy in paper-making machines,

2

where relatively large quantities of steam at atmospheric pressure and containing air are given off (as from an M. G. cylinder). Such steam may be passed through a heat interchanger as described above to raise steam at a pressure less than atmospheric, such steam being drawn by a pump to maintain the pressure within the heat interchanger at a value less than atmospheric and then to increase its pressure on discharge from the pump. Thus, for example, steam in the heat interchanger may be raised at a pressure of 5 lbs. less than the atmosphere and may be discharged from the pump at 10 lbs. per sq. inch above atmosphere. The steam discharged by the pump may be fed back to the M. G. cylinder to heat the same, and the condensate from the M. G. cylinder may be returned to the heat interchanger and again converted into steam, whereby loss of both latent and sensible heat is, to a material extent, avoided. 15

The invention is not however applicable solely to vapours at low pressure.

Thus, in an industrial process where steam or other vapour is used so as to reduce its pressure from a higher pressure to a lower pressure, one feature of the present invention consists in mechanically increasing the pressure of the steam after it has been used to enable it to be re-used for the same or a different purpose, or to enable it to be re-used more efficiently for the same or a different purpose. 20

Again, in an industrial process where steam or other vapour at one pressure is produced by the consumption of steam or other vapour at a higher pressure, a further feature of the invention consists in increasing the pressure of said produced steam or other vapour mechanically to enable it to be used for the purpose for which said consumed steam was used or for some other purpose. 25

The invention is further described with reference to the accompanying drawings in which the figure is a diagrammatic illustration of how the invention can be applied to a drying roll of a paper-making machine. 30

The figure illustrates diagrammatically a drying roll 1 of a paper-making machine having a hood 2 thereabove to entrap the mixture of vapour and air which is given off as a result of drying. The drying roll 1 is steam heated and the steam is initially supplied to the roll through valve 3 and pipe line 4. The mixture of vapour and warm air entrapped in the hood 2 is drawn by a fan 5 into a heat interchanger casing 6 through which passes a coiled tube 7 to which water is fed at the end 8. The fan 5 causes the mixture of vapour and air to flow at high velocity in closed circuit as illustrated by the arrows 9, 10 and 11 with a volume rate of flow which is high as compared with the rate of inflow of the mixture from the hood 2 and preferably a multiple thereof. By virtue of the rapid re-circulation of the air-vapour mixture in the heat interchanger casing 6 it is possible to raise steam in the coil 7 at a temperature not greatly less than the temperature of the circulating mixture. The outlet end 12 of the tube 7 is connected to a compressor 13 which discharges through a valve 14 to the pipe line 4 so that when the valve 14 is open and the valve 3 is closed or partially closed the compressor will deliver steam to the drum 1. 45

It will be appreciated that the compressor serves to facilitate the generation of steam by the maintenance of a low pressure in the tube 7. This pressure is preferably less than atmospheric, for example pressure may be 5 lbs. per sq. inch below atmosphere, and the compressor may raise the pressure of the steam thus generated to pressure of say 5 lbs. per sq. inch above atmosphere. 50

If desired the condensate from the drum 1 may be fed to the tube 7 whereby to avoid loss of the sensible heat of the condensate. Likewise condensate from the casing 6

may be drawn off from the drain 15 and fed to the tube 7.

I claim:

1. In a paper making process wherein paper in the course of production is passed over drying rolls heated by steam, and results in the production of a mixture of water vapor and air outside the drying rolls, the step of withdrawing said mixture into a closed chamber having a heat exchanging means passing therethrough, the step of circulating said mixture within said chamber about said means at a velocity in excess of the velocity at which said mixture enters said chamber, the step of generating steam within said means by reducing the pressure therein to a point at which the temperature of said circulating mixture will vaporize water within said means to form steam, the step of withdrawing said steam from said means at said reduced pressure and subsequently increasing the pressure of said steam, and the step of using said steam at increased pressure to achieve further drying.

2. In a paper making process according to claim 1, the step of generating the said steam at a pressure less than that of the atmosphere and the step of using mechanical means such as a pump to maintain the low pressure of the steam being generated and to increase its pressure after it has been generated.

3. In a paper making machine including a steam heated drying roll having a hood enclosing at least an upper portion thereof to collect at least some of a mixture of water vapour and air produced as a result of drying, the provision of a heat interchanger including means to receive a mixture of water vapour and air from said hood, at least one steam generating passage in said heat interchanger, means to feed water into said steam generating passage, and means to permit the withdrawal of steam therefrom, means to circulate said mixture in said heat interchanger in a closed circuit in heat interchange relationship with said steam generating passage, and a pump connected at its inlet side to said steam generating passage to enable said pump to draw steam at low pressure from said steam generating passage and to deliver it at increased pressure to achieve further drying.

4. In a paper making machine including a steam heated drying roll having a hood enclosing at least the upper portion thereof to collect at least some of a mixture of water vapour and air produced as a result of drying, the provision of a heat interchanger casing, at least one steam generating tube contained in said casing, an inlet in said casing to receive at least some of said mixture of water vapour and air from said hood, a drain connection to said casing to permit removal of condensed water vapour out of said mixture, a water inlet connection to said steam generating tube, a steam outlet connection from said steam generating tube, a fan adapted to draw a mixture of water vapour and air from said hood and to circulate it in closed circuit through said casing and to cause it to impinge at high velocity on said steam generating tube with a volume rate of flow greater than and preferably a multiple of the rate at which said mixture is drawn off from said hood and a pump connected at its inlet side to the steam outlet of said steam generating tube to enable said pump to draw steam at low pressure from said steam generating tube and to deliver it at increased pressure to achieve further drying.
